UNITED STATES PATENT OFFICE.

CHARLES H. DE LANCEY, OF BINGHAMTON, NEW YORK.

MUFFLER.

Application filed June 27, 1921. Serial No. 480,794.

To all whom it may concern:

Be it known that I, CHARLES H. DE LANCEY, a citizen of the United States, residing at Binghamton, in the county of Broome and State of New York, have invented certain new and useful Improvements in Mufflers, of which the following is a specification.

This invention relates to mufflers, and 10 more particularly to a muffler having an ejector or ejectors in combination therewith, to assist in expanding and cooling exhaust gases.

An object of the present invention is to 15 provide a muffling device that will effectually silence the sound of exhaust gases or vapors from an internal combustion engine, or other engine, or boiler escape pipe.

A further object is to provide a muffler 20 which will effectually silence the sound of exhaust gases or vapors without creating a back pressure.

The muffler herein disclosed is especially 25 designed for use on high speed engines, such as are used on racing automobiles, motor boats, and air craft, but it may be employed on motor vehicles of any type.

A further object of the invention is the 30 provision of a muffler in which the passage therethrough is not obstructed by baffle plates or similar devices heretofore employed in devices of this character.

In the accompanying drawings, I have 35 shown several embodiments of the invention.

Figure 1 is a central longitudinal sectional view.

Figure 2 is a transverse sectional view on line 2—2 of Figure 1.

Figure 3 is a similar view on line 3—3 of Figure 1.

Figure 4 is a similar view on line 4—4 of Figure 1.

Figure 5 is a similar view on line 5—5 of Figure 1.

Figure 6 is a detail sectional view.

Figure 7 is a longitudinal sectional view of another form of the invention, and,

Figure 8 is a similar view of another 50 form of the invention.

Referring to Figures 1 to 6 the drawings, the reference numeral 1 designates an outer casing or shell which, as shown, may be cylindrical in form, or may be made any other desired shape. An end wall 2 is secured to the muffler casing by any suitable

means such as a threaded collar 3 adapted to engage the threads formed on the ejector casting and the end of the casing, as shown. The end wall 2 of the ejector is provided 60 with a central opening, and a nozzle 4 is arranged within this opening and projecting into the casing. The nozzle is retained in position by means of a threaded collar 5, the collar being provided with internal 65 threads by means of which the muffler is secured to the exhaust pipe 6. The ejector is further provided with a slightly flaring tubular member 7, forming a central passage communicating with the end of the 70 nozzle 4. The butt end of the tubular member is enlarged, as at 8, to conform to the outline of the nozzle, and is spaced from the nozzle to provide a circular port 9. The port 9 communicates with a circular cavity 75 within the ejector, which in turn communicates with the expansion space 10 of the muffler by means of a plurality of openings 11, through the wall 12 of the ejector cavity. 80

The tubular member 7 terminates intermediate the ends of the casing, and a plurality of disks 13 having central openings 14, are supported on rods 15. The inner ends of the rods are mounted in the end of the 85 tubular member 7, the outer ends being received in a plate 16, arranged near the outlet end of the casing. Adjacent the tubular member, the disks 13 are curved on a single arc to deflect exhaust gases passing into 90 the expansion chamber 10 toward the openings 11. As shown, the disks are slightly spaced from each other, being maintained in spaced position by means of washers 17. At a point adjacent to the outlet end of the 95 casing, a plurality of spaced disks 18 are provided. These disks are also mounted on the rods 15 and maintained in spaced position by washers 17. As shown, the disks 18 consist of inner portions curved in the 100 same direction as the disks 13 to direct the exhaust gases outwardly into the expansion chamber. The outer portions of the disks are, however, curved in the opposite direction, as at 19, in Figure 6, to direct the gases 105 toward the outlet end of the muffler casing.

A nozzle 20 is arranged in alignment with the openings 14 in the disks, the nozzle being provided with a flange 21 for the reception of rods 15, whereby the nozzle is retained 110 in position. Surrounding the nozzle, there is provided an outer nozzle 22, having a

threaded end 23, adapted to engage threads formed on the end of the casing. The plate 16 is provided with openings 24 to permit passage of gases from the expansion chamber into space 25 between the two nozzles.

Figure 7 shows a different arrangement for delivering the gases from the central exhaust passage into the expansion chamber 10. The disks 13 and 18 are eliminated and 10 a perforated pipe 26 is employed, the pipe being secured to the end of the tubular member 7 by suitable fastening means, as indicated at 27, and being provided with a plurality of openings 28. A spiral core 29 15 is arranged within the pipe whereby the exhaust gases are passed through the pipe in a spiral path, and delivered through the openings 28 into expansion chamber 10 by centrifugal force as well as by their own expansive force.

As shown, in Figure 8 of the drawings, the spiral core 29 may be employed in connection with the disks 13 and 18.

In the operation of the form of the invention shown in Figures 1 to 6 of the drawings, the exhaust gases delivered through pipe 6 pass through nozzle 4 at a high rate of speed, forming a suction through the circular port 9 and drawing exhaust gases 25 from the expansion chamber 10 through openings 11 into the tubular member 7, overcoming any vacuum therein. The exhaust gases drawn from the expansion chamber are cooled and expanded and tend to cool 30 and contract the hot exhaust gases from exhaust pipe 6 in the tubular member 7. As the exhaust gases pass into the passage formed by openings 14 in the disks, the major portion of them are forced through the 35 space between the disks by expanding into the expansion chamber 10. The first set of disks 13 deflect the gases toward the inlet end of the muffler, and the disks 18 deflect them in an opposite direction toward the outlet end. The nozzles 20 and 22 operate as 40 an ejector so that the portion of exhaust gases passing between the disks 18 are drawn through the openings 24 into the space 25 and delivered to the atmosphere. 45 That portion of the exhaust gases which passes directly through the central exhaust passage is delivered through the nozzle 20, and produce a suction in the space 25, drawing the exhaust gases from the expansion 50 chamber. By means of the ejectors arranged at each end of the muffler, the expansion chamber 10 is kept practically free of gases, allowing a very rapid expansion of the exhaust gases as they are delivered into the expansion chamber, thus permitting the exhaust gases to be greatly expanded and cooled, and pass practically noiseless, into the atmosphere.

It will be seen that by means of the construction herein disclosed, a muffler is pro-

vided by means of which the exhaust gases are expanded and cooled without obstructing the exhaust passage in any way.

In the form of the invention shown in Figure 7 of the drawings, the operation of the 70 ejector at the inlet end of the muffler is the same, and the gases passing through the tubular member enter the perforated pipe 26, are divided by the spiral core 29, and caused to pass through the pipe in a spiral path, 75 the major portion of the gases being driven through the openings 28 into the expansion chamber by the centrifugal action of the gases whirling around through the spiral cavity, as well as by the force of expansion, 80 whence the gases are delivered to either of the ejectors in the manner heretofore described.

In the form of the invention shown in Figure 8 of the drawings, the operation is 85 substantially the same as in the form shown in Figures 1 to 6, except that the volume of gas expanding into expansion chamber 10 between the disks 13 and 18 is materially increased by the centrifugal action of the gases whirling around through the spiral path formed by the spiral cores 29.

It is to be understood that the forms of my invention herewith shown and described are to be taken as preferred examples of the same, and that various changes in the shape, size, and arrangement of parts may be resorted to without departing from the spirit of my invention or the scope of the subjoined claims.

Having thus described my invention, I claim:

1. A muffler comprising a casing, a substantially unobstructed exhaust passage extending through the casing, an expansion chamber surrounding said exhaust passage and communicating therewith at a plurality of points to receive exhaust gases therefrom, and an ejector arranged at the inlet end of said exhaust passage and forming a continuation thereof, said ejector being operated by the full force of the exhaust gases to withdraw gases from the expansion chamber.

2. A muffler comprising a casing, a substantially unobstructed exhaust passage of substantially uniform diameter extending through the casing, an expansion chamber surrounding said exhaust passage and communicating therewith to receive exhaust gases therefrom, and an ejector arranged at the inlet end of the exhaust passage and communicating therewith whereby all the exhaust gases pass into said exhaust passage upon entering said casing, said ejector being adapted to withdraw gases from said expansion chamber and returning them to the exhaust passage.

3. A muffler comprising a casing having an exhaust passage arranged therein, an expansion chamber surrounding said exhaust

- passage and communicating therewith to receive exhaust gases therefrom, an ejector arranged at the inlet end of the exhaust passage and communicating therewith whereby
- 5 all the exhaust gases pass into said exhaust passage upon entering said casing, said ejector being adapted to withdraw gases from said expansion chamber and return them to the exhaust passage, and an ejector arranged
- 10 at the outlet end of the exhaust passage to withdraw gases from the opposite end of the expansion chamber.
4. A muffler comprising a casing having an exhaust passage extending therethrough, an expansion chamber surrounding said exhaust passage and communicating therewith, means for permitting passage of gases from said exhaust passage into said expansion chamber at a point remote from the
- 20 inlet end of said casing, an ejector arranged at the inlet end of said casing and forming a continuation of said exhaust passage whereby all gases entering said casing are delivered to said exhaust passage, said ejector being adapted to withdraw gases from said expansion chamber adjacent said inlet end and return them to said exhaust passage.
5. A muffler comprising a casing, a tubular member arranged in said casing and extending from the inlet end of the casing to a point intermediate the ends, said tubular member forming a central exhaust passage and a surrounding expansion chamber, means for forming an exhaust passage from the inner end of said tubular member to the outlet end of the casing and to permit communication between the exhaust passage and the expansion chamber, a nozzle extending into the inlet end of the casing and spaced from the end of said tubular member to form an ejector to withdraw exhaust gases from the expansion chamber, and a nozzle formed on said outlet end of the exhaust passage to withdraw exhaust gases from the adjacent portion of the expansion chamber.
6. A muffler comprising a casing, a tubular member arranged within the casing and spaced therefrom to provide an exhaust passage and a surrounding expansion chamber, said tubular member extending to a point adjacent the inlet end of the casing to a point intermediate the ends of the casing, a plurality of spaced disks arranged in alignment with said tubular member and extending to the outlet end of the casing, said disks being provided with central openings to provide a continuation of the exhaust passage, the spaces between said disks being adapted to permit communication between the exhaust chamber and the expansion chamber, and an inlet comprising a

nozzle arranged concentric with said tubular member and spaced from the end of said tubular member to permit return of gases from the expansion chamber to the exhaust

7. A muffler comprising a casing, a tubular member arranged in said casing and extending from the inlet end of the casing to a point intermediate the ends, said tubular member forming a central exhaust passage and a surrounding expansion chamber, means for forming an exhaust passage from the inner end of said tubular member to the outlet end of the casing, said exhaust passage being provided with openings to permit passage of gases into the expansion chamber, a spiral core arranged within said exhaust passage, a nozzle extending into the inlet end of the casing and spaced from the end of said tubular member to form an ejector to withdraw gases from the expansion chamber, and a nozzle formed on said outlet end of the exhaust passage to withdraw gases from the adjacent portion of the expansion chamber.

8. A muffler comprising a casing having a central exhaust passage, an expansion chamber surrounding said exhaust passage, means for permitting passage of gas from said exhaust passage into said expansion chamber, and ejectors arranged at the ends of the casing to withdraw gases from the expansion chamber by the force of the exhaust gases passing through the central exhaust passage.

9. A muffler comprising a casing, a tubular member arranged therein and extending from the inlet end of the casing to a point intermediate the ends, said tubular member forming a central exhaust passage and a surrounding expansion chamber, a member forming an exhaust passage communicating with the end of said tubular member and extending to the outlet end of the casing, said member being provided with openings to permit passage of gases into the expansion chamber, a nozzle extending into the inlet end of the casing and spaced therefrom, and a wall formed on the end of said tubular member cooperating with said nozzle to form an ejector to withdraw gases from the expansion chamber and return them to the central exhaust passage adjacent the inlet end of the casing.

In testimony whereof I affix my signature in presence of two witnesses.
